UNITED STATES PATENT OFFICE.

ALADAR HOLLANDER, OF NEW LONDON, CONNECTICUT, ASSIGNOR TO ELECTRIC BOAT COMPANY, OF NEW YORK, N. Y., A CORPORATION OF NEW JERSEY.

PERISCOPE.

1,290,745.

Specification of Letters Patent.

Patented Jan. 7, 1919.

Application filed April 12, 1916. Serial No. 90,543.

To all whom it may concern:

Be it known that I, ALADAR HOLLANDER, a citizen of Hungary, and a resident of New London, in the county of New London and 5 State of Connecticut, have invented certain new and useful Improvements in Periscopes; and I do hereby declare the following to be a full, clear, and exact description of the invention, such as will enable others 10 skilled in the art to which it appertains to make and use the same.

This invention relates to improvements in periscopes and particularly to periscopes for submarine vessels.

15 Submarine vessels as now constructed are provided with conning towers projecting above the upper wall of the hull or deck of the vessel in which tower the commanding officer usually takes his position when the 20 vessel is cruising on the surface or running with the decks awash, making his observations either through port lights in the wall of the conning tower or directly through the open roof of the tower if the weather permits. 25 For observations when wholly submerged, the vessels are provided with periscopes projecting to a height considerably above the conning tower.

Except when observations from the conning tower are necessary the direction of the boat can be better accomplished from a 30 position within the hull of the vessel, hence the eye-piece of the periscope is located outside the conning tower inclosure and preferably immediately beneath the floor. It is 35 frequently desirable, particularly when the boat is being submerged, for the officer in the conning tower to be able to make for himself observations from the more elevated 40 position of the periscope objective, and to make such observations it has heretofore been necessary to provide the conning tower with a separate auxiliary periscope. Such construction is, however, open to the objection 45 not only of additional cost, but because it takes up space in a vessel where every inch of space must be utilized, adds to the resistance of the vessel when running submerged and offers an additional visible part

for detection when the vessel is in hostile 50 waters.

The object of the present invention is to provide a periscope construction having but a single outboard part by means of which observations may be made either from a 55 position in the conning tower or from the main portion of the hull of the vessel.

A further object of the invention is to provide a periscope of this character which will occupy little room in the conning tower 60 when arranged for observations from the tower and which may be quickly and easily adjusted for observation from either position.

A further object of the invention is to 65 provide a periscope in which the upper part may be vertically adjustable to permit the objective to be projected out of the water without changing the depth of submergence of the vessel, while the eye-piece within the 70 hull of the boat remains stationary, thereby requiring less space in the vessel and reducing the weight to be shifted.

With the above objects in view, my invention consists of the device shown in the accompanying drawings and hereinafter described, it being of course understood that the invention is not limited to the details of construction disclosed, except so far as is pointed out in the appended claims. 80

In the said drawings,

Figure 1 is a longitudinal section through the conning tower and a portion of the hull of a submarine vessel equipped with my improved periscope, the periscope being shown 85 in side elevation;

Fig. 2 is an enlarged detail view in vertical section of the upper eye-piece with the shiftable portion of the periscope adjusted for observations through such eye-piece. 90

Fig. 3 is a vertical section through the lower eye-piece; and

Fig. 4 is a horizontal sectional view on line 4-4 of Fig. 2.

Referring to the drawings, particularly 95 to Fig. 1, 1 indicates the upper wall of the hull or deck of the submarine on which is supported the outboard portion 2 of the con-

ning tower. The conning tower inclosure is continued below the vessel by the shell 3 to give the desired head room in the conning tower. Access to the interior of the conning tower from the interior of the vessel is had through a hatchway 4 having an air- and water-tight closure as illustrated, to prevent flooding of the entire vessel in case of damage to the conning tower.

10 The top of the conning tower is provided with an observation opening indicated at 5 and may also if desired be provided with suitable port openings, not shown, permitting observations to be made without opening 15 the cover 6.

The periscope of my present invention comprises a tube 7 supported for vertical movement in a tubular standard 8 mounted on the top wall of the conning tower, packed 20 bearings 9 being provided at each end of the column 8 to prevent leakage of water into the conning tower when the vessel is submerged.

Attached to the upper end of the tube 7 25 is the usual objective comprising a casing 10 supporting the lenses and reflecting prism for directing the laterally received rays down the periscope. The periscope tube is rotatably supported in a bearing ring 11 suspended by cables 12 running over pulleys 13 supported from the roof of the conning tower on either side of the periscope 7. The bearing ring 11 engages the periscope tube 7 immediately above its lower end, 30 the tube resting on ball bearings as indicated in Fig. 2 to permit its easy rotary adjustment. Attached to the lower end of the tube is a prism-carrying extension 14 of circular cross-section and of a diameter somewhat larger than the bearing ring 11. The lower end of the extension 14 is closed by 35 a suitable web which supports the prism 15 in proper position in the optical system of the periscope to reflect the rays laterally through the opening 16 in the wall of the extension 14.

The eye-piece lenses for making observations from within the conning tower are supported in an eye-piece casing 17 independently suspended from the roof of the 50 conning tower by a fixedly supported ring 18, the casing 17 being rotatable in the ring 18, as shown in Fig. 2. The internal diameter of the casing 17 is just sufficiently larger 55 than the external diameter of the prism-carrying extension 14 for the extension to have a sliding fit in the casing when the periscope tube is in its elevated position shown in the drawings. For maintaining 60 the casing and prism-holder in proper registration the extension 14 is provided with a fixed key 19 which engages a keyway in the inner face of the casing 17.

For permitting observations to be made

through the periscope from a point outside 65 the conning tower, I have provided auxiliary eye-piece lenses supported in a shell or casing 20 rotatably suspended from the floor of the conning tower in alinement with the axis of the periscope tube. The casing 20 70 is of an internal diameter to have a sliding fit with the extension 14 when the periscope tube is lowered and is provided along the inner face opposite the lenses with a suitable keyway 21 for receiving the key 75 19. The lower end of the casing 10 is provided with an air- and water-tight closure which serves also as a stop for the bottom of the periscope tube to properly position the prism with regard to the lenses of the 80 eye-piece.

The cables 12 which support the bearing ring 11 are trained over a pair of pulleys 22 near the side wall of the conning tower, and below the pulleys 22 the two cables 12 85 are connected together as indicated at 23, the single extending cable passing through a stuffing-box in the floor of the conning tower. The cable passes thence over two pulleys 24 beneath the conning tower, then up through a stuffing box in the bottom of the casing 20, the end of the cable being connected to an eye 25 depending from the prism-carrier 14. The cable may be provided with a suitable counterweight 95 for counterbalancing the weight of the periscope tube, or one of the pulleys 24 may be driven by a chain or belt as indicated at 26 from a compressed air or electric motor not shown, or in any other suitable manner. 100

When the vessel is running with the decks awash or is being submerged, and the officer in charge is located in the conning tower, the periscope is raised to its upper position so that it may be used for more distant observations than can be made through the hatchway at the top of the conning tower. For such use, the tube is raised to its fullest extent, which may be accurately determined by the engagement of the key 19 with the 110 top of the keyway in the eye-piece casing 17. The position of the ring 18 will be fixed so that the periscope tube will lift the casing 17 slightly so that the entire weight will be supported by the ball bearings in the 115 ring 11.

When it is desired to make observations through the periscope from the interior of the vessel, the periscope tube will be lowered until the bottom edge of the prism-holder 14 is stopped by the end closure of the casing 20, the casing being rotated to bring the key 19 into registration with the keyway 21, to position the reflecting face of the prism in front of the lenses. 120

It will of course be understood that the casing 20 is supported in an air- and water-tight stuffing box, and that the guides of 125

the cable through the floor of the conning tower and the bottom of the casing are similarly packed.

If a motor is employed for elevating and 5 lowering the periscope tube it will of course be provided with suitable controlling devices located preferably both within and without the conning tower, for convenience of operation.

10 I claim:

1. In a submarine boat, a conning tower having a floor elevated above the floor of the boat, a periscope comprising a tube projecting through the roof of the conning tower

15 and provided with an outboard objective, an eyepiece supported in the conning tower, a second eyepiece supported in the body of the boat beneath the floor of the conning tower and vertically beneath the first mentioned 20 eyepiece, and optical means forming part of the optical system of the periscope whereby images through said objective may be viewed through either of said eyepieces.

2. In a submarine boat, a conning tower 25 having a floor elevated above the floor of the boat, a periscope comprising a tube projecting through the roof of the conning tower and provided with an outboard objective, an eyepiece supported in the conning tower, a second eyepiece supported in the body of the boat beneath the floor of the conning tower and vertically beneath the first mentioned 30 eyepiece, and optical means comprising one adjustable element forming part of the optical system of the periscope whereby the images through said objective may be directed in their full strength to either eyepiece.

3. In a submarine boat having a conning 40 tower, the combination of a periscope tube projecting above the conning tower and provided with an outboard objective, an eyepiece carried by said tube in the conning tower, a second eyepiece supported below the 45 conning tower, said periscope comprising optical means including a shiftable reflector whereby the image received through the objective may be viewed through either eyepiece.

50 4. In a periscope the combination of a periscope tube having an objective at its upper end and a plurality of eye-pieces arranged one above the other, the optical elements of said periscope comprising a movably mounted reflector adapted to be adjusted into optical registration with either of said eye-pieces.

5. In a periscope the combination of a 60 periscope tube having an objective and a reflector, a plurality of eye-pieces mounted one above the other, and means for adjusting said periscope tube to bring said reflector into optical registration with either of said eye-pieces.

6. In a periscope the combination of a 65 periscope tube mounted for longitudinal adjustment and having an objective at one end and a reflector at the other, a plurality of eye-pieces arranged vertically one above the other, the upper eye-piece comprising a 70 casing surrounding said periscope tube and having a lateral opening registering with the reflector in one position of adjustment of said tube, said casing being of sufficient diameter to permit the adjustment of the periscope tube through the casing to bring its reflector into optical registration with the second eye-piece.

7. In a periscope the combination of a 75 periscope tube mounted for longitudinal and rotary movement, said tube having an objective at its upper end and a reflector at its lower end, a plurality of eye-pieces independently mounted for rotary movement one above the other, said upper eye-piece embodying a casing surrounding the periscope tube, and locking means carried by said tube and said eye-pieces respectively, connecting the tube with either eye-piece for rotation as a unit with the reflecting face of the 80 reflector facing the optical elements of the eye-piece.

8. In a submarine boat having a conning tower, a periscope comprising a tube projecting above said conning tower, said tube 95 having an objective at its upper end and a reflector at its lower end, an eye-piece supported in said conning tower, and a second eye-piece supported with its lens opening without the conning tower inclosure, said 100 periscope tube being adjustable to bring its reflector into optical registration with either of said eye-pieces.

9. In a submarine boat having a conning tower, a periscope comprising a tube projecting above said conning tower and mounted for vertical movement in the roof of said conning tower, said periscope tube having an objective at its upper end and a reflector at its lower end, an eye-piece independently supported in said conning tower, a second eye-piece supported in the floor of said conning tower with its lens opening without the conning tower inclosure, said 105 eye-pieces being arranged so that by vertical 110 adjustment of the periscope tube its reflector may be shifted from optical registration with one of said eye-pieces to optical registration with the other.

10. In a submarine boat having a conning 120 tower a periscope comprising a tube projecting through the wall of said conning tower and provided with an objective at its outer end and a reflector at its inner end, said periscope being mounted for longitudinal movement, an eye-piece comprising a casing surrounding said periscope tube and supported independently thereof, said

casing having a lateral opening adapted to register with the reflector of said periscope tube, said casing being of a diameter sufficient to permit the longitudinal adjustment 5 of the periscope tube through the casing, and a second eye-piece comprising a casing in position to register with the periscope tube

at its extreme position of longitudinal adjustment, said casing having a lateral opening without the conning tower inclosure and positioned to register with the reflector of the periscope tube. ¹⁰

In testimony whereof I affix my signature.
